(57) **CLAIM**

The ornamental design for a display screen with an animated avatar, as shown and described.

DESCRIPTION

FIG. 1 is a front view of the first image in the sequence for a display screen with an animated avatar showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of the ninth image thereof;

FIG. 10 is a front view of the tenth image thereof;

FIG. 11 is a front view of the eleventh image thereof;

FIG. 12 is a front view of the twelfth image thereof;

FIG. 13 a front view of is the thirteenth image thereof;

FIG. 14 is a front view of the fourteenth image thereof;

FIG. 15 is a front view of the fifteenth image thereof;

FIG. 16 is a front view of the sixteenth image thereof;

FIG. 17 is a front view of the seventeenth image thereof; and,

FIG. 18 is a front view of the eighteenth image thereof.

The appearance of the animated avatar sequentially transitions between the images shown in FIGS. 1-18. The process or period in which one image transitions to another forms no part of the claimed design. The broken line showings of a portion of the display screen, the seat back, and portions of the avatar are for the purpose of illustrating unclaimed portions of the display screen with an animated avatar and form no part of the claimed design.
